(57) **CLAIM**

The ornamental design for a knee guard, as shown.

DESCRIPTION

FIG. 1 depicts an isometric view of the knee guard from above and to the side whilst it is coupled to a leg brace.

FIG. 2 depicts an isometric view of the knee guard from below and to the side whilst it is coupled to a leg brace.

FIG. 3 depicts a direct view of the knee guard from the right side whilst it is coupled to a leg brace.

FIG. 4 depicts a direct view of the knee guard from the left side whilst it is coupled to a leg brace.

FIG. 5 depicts an exploded view of the knee guard from below and to the side whilst it is coupled to a leg brace.

FIG. 6 depicts an exploded view of the knee guard from the left side whilst it is coupled to a leg brace.

FIG. 7 depicts an exploded view of the knee guard from the right side whilst it is coupled to a leg brace.

FIG. 8 depicts an isometric view of the knee guard on its own from below and to the side.

FIG. 9 depicts an isometric view of the knee guard on its own from above and to the side.

FIG. 10 depicts a view of the knee guard on its own from directly below.

FIG. 11 depicts a direct view of the knee guard on its own from the right side.

FIG. 12 depicts a view of the knee guard on its own from directly behind.

FIG. 13 depicts a view of the knee guard on its own from directly above.

FIG. 14 depicts a direct view of the knee-guard on its own from the left side; and,

FIG. 15 depicts a view of the knee guard on its own from directly in front.

The broken line showing is included for the purpose of illustrating environment and forms no part of the claimed design.
